DESIGN FOR A TIRE

Glenn Hullinger, Shreveport, La., assignor to
Arkansas Fuel Oil Company, Shreveport, La.,
a corporation of West Virginia

Application July 14, 1938, Serial No. 78,479

Term of patent 14 years

To all whom it may concern:

Be it known that I, Glenn Hullinger, a citizen of the United States, residing at Shreveport, in the parish of Caddo and State of Louisiana, have invented a new, original, and ornamental Design for a Tire, of which the following is a specification, reference being had to the accompanying drawing, forming part thereof.

Figure 1 is a perspective view of a tire the

portion shown in dotted lines being partly cut away for convenience in illustration.

Fig. 2 is a plan view of a section of the tire, and
Fig. 3 is a sectional view taken on the line
III—III of Fig. 2.

I claim:
The ornamental design for a tire, as shown.

GLENN HULLINGER.
